UNITED STATES PATENT OFFICE.

ACHILLE KAISERMAN, OF ROCHELLE, ILLINOIS.

DESIGN FOR A PICTURE-FRAME.

No. 40,136.

Specification for Design.

Patented July 13, 1909.

Application filed May 1, 1909. Serial No. 493,444. Term of patent 14 years.

To all whom it may concern:

Be it known that I, ACHILLE KAISERMAN, a citizen of the United States, residing at Rochelle, in the county of Ogle and State of Illinois, have invented a new, original, and ornamental Design for a Picture-Frame, of which the following is a specification, reference being had to the accompanying drawing, forming part thereof.

The figure is a perspective view of a picture frame showing my design.

I claim:

The ornamental design for a picture frame, as shown.

ACHILLE KAISERMAN.
